(57) **CLAIM**

The ornamental design for an electric bike, as shown and described.

DESCRIPTION

FIG. 1 is a front and left side perspective view of an electric bike embodying our new design;

FIG. 2 is a front and right side perspective view thereof;

FIG. 3 is a top plan view thereof;

FIG. 4 is a front elevational view thereof;

FIG. 5 is a left side elevational view thereof; and,

FIG. 6 is a right side elevational view thereof.

The broken lines in the drawings illustrate portions of the electric bike that form no part of the claimed design.
